R. D. GILLETTE.
BEADING MACHINE.
APPLICATION FILED JULY 22, 1916.

1,226,508.

Patented May 15, 1917.

UNITED STATES PATENT OFFICE.

ROBERT D. GILLETTE, OF ST. CHARLES, MISSOURI.

BEADING-MACHINE.

1,226,503.

Specification of Letters Patent.

Patented May 15, 1917.

Application filed July 22, 1916. Serial No. 110,760.

To all whom it may concern:

Be it known that I, ROBERT D. GILLETTE, a citizen of the United States, residing at St. Charles, in the county of St. Charles, State 5 of Missouri, have invented a certain new and useful Beading-Machine, of which the following is a specification.

This invention relates to improvements in those machines employed in the manufacture 10 of shoes for the purpose of beading the tops thereof adjacent to the seam which connects the upper to the canvas or other lining, and the object of the invention is to afford a machine capable of performing this 15 work by the application of continuous pressure over a comparatively large surface, as distinguished from the hammer-like operation of beaders heretofore used wherein the upper must be moved from side to side by 20 the operator and as further distinguished from those machines which employ rollers for the purpose described.

A further object is the provision of a machine of this character whose construction 25 and operation is such that the operator may easily avoid damage to the back-seam which frequently results where the beading is accomplished by aid of prior machines due to the compression of the stitching.

Other objects and advantages may be noted in the following parts of the specification and are particularly pointed out in the appended claims.

In the accompanying drawing, wherein 35 like numerals refer to like parts throughout the several views, Figure 1 is a top plan view; Fig. 2 is a front elevation; Fig. 3 a side elevation; Fig. 4 a rear elevation; Fig. 5 is a vertical section along line 5—5 of Fig. 2; Fig. 6 a cross-sectional view along line 6—6 of Fig. 5; Fig. 7 a fragmentary vertical section along line 7—7 of Fig. 2; and Fig. 8 a plan view of the upper and its lining for the purpose of making clear the 45 function of the machine.

In the practice of my invention I provide a peculiarly shaped casting 1 which is secured upon the work-bench 2 by bolts 3 passing through its base at the rear. Projecting vertically through said casting is a shaft 4 whose lower extremity carries the clutch element 5 which may be engaged by operation of rod 6 with clutch element 7 driven by shaft 8. By reference to Fig. 5 it 55 will be noted that cam-rollers 9 and 10 are

carried by shaft 4, roller 9 being located opposite a pin 11 projecting from the presser-foot 12, and roller 10 disposed adjacent to an extremity of a curved arm 13 which is pivoted at 14 and extends through a slot 15 in the standard 16. Presser-foot 12 is suspended from the top of the casting by three helical springs, one of which is shown at 17 in Figs. 2 and 5, while arm 13 is connected with and subjected to the pull of spring 18 whose lower end is fastened to a stationary lug or eyelet 19.

The center of standard 16 is slotted for the insertion therein of posts 20—21 which support the bearing-plate 22, and adjustment of the latter with respect to presser-foot 12 may be effected through the agency of cams 23—24 which are formed at the inner end of threaded rods 25—26 and bear against the beveled extremity 27 of said 75 posts when drawn outwardly by turning members 28—29. Thus the pressure may be regulated and either thin or thick materials accommodated.

In operation the upper 30 is folded over 80 the lining 31 and the latter is then inserted over the edge of plate 32 which is affixed to the upper end of arm 13 and corresponds in width to the bearing-plate 22. This having been done, the operator then engages the 85 clutch elements 5 and 7 to effect rotation of shaft 4 and movement of the latter serves to subject pin 11 and the inner extremity of pivoted arm 13 to the action of cam-rollers 9 and 10. The latter are of such size and 90 formation as to depress said extremity of arm 13 and thus carry the upper and its lining inward upon plate 22 simultaneous with the commencement of the descent of presser-foot 12 which is effected through the agency 95 of pin 11. When foot 12 engages the upper, arm 13 is released from the action of roller 10 and drawn outwardly by spring 18, while the beading is accomplished through the continued pressure of said foot until pin 11 has 100 traversed the enlarged portion of roller 9, whereupon the operation is repeated with respect to the remainder of the top edge. It will thus be appreciated that, as the 105 presser-foot in the preferred embodiment of my invention is but half as long as the edge of the upper, the operator is enabled to prevent damage to the back-seam by simply disposing the same beyond the end of plate 22 before effecting the descent of said foot.

Having thus fully described the invention, what I claim as new and desire to secure by Letters-Patent is:—

1. A machine of the character described comprising a presser-foot, a bearing-plate disposed therebeneath, means for depressing said foot, devices for automatically retracting the same, and mechanism for vertically adjusting said plate relative to said foot.
- 10 2. A machine of the character described comprising a presser-foot, a bearing-plate disposed therebeneath, an arm, means for projecting an extremity thereof between said foot and plate, means for depressing said foot, and devices for automatically retracting the same.
- 20 3. A machine of the character described comprising a presser-foot, a bearing-plate disposed therebeneath, an arm, means for projecting an extremity thereof between said foot and plate, means for depressing said foot, devices for automatically retracting the same, and mechanism for vertically adjusting said plate relative to said foot.
- 25 4. A machine of the character described comprising a presser-foot, a bearing-plate disposed therebeneath, a pin extending from said foot, a shaft, a cam-roller secured thereto adapted to depress said pin, and springs adapted to lift said foot upon release of said pin.
- 30 5. A machine of the character described

comprising a presser-foot, a bearing-plate disposed therebeneath, a pin extending from said foot, a shaft, a cam-roller secured thereto adapted to depress said pin, springs adapted to lift said foot upon release of said pin, posts supporting said plate, and cams disposed beneath said posts adapted to raise the same.

40 6. A machine of the character described comprising a presser-foot, a bearing-plate disposed therebeneath, a pin extending from said foot, an arm adapted to project between said foot and plate, a shaft, cam-rollers secured thereto adapted to depress said pin and actuate said arm, and springs adapted to lift said foot upon release of said pin and withdraw said arm.

45 7. A machine of the character described comprising a presser-foot, a bearing-plate disposed therebeneath, a pin extending from said foot, an arm adapted to project between said foot and plate, a shaft, cam-rollers secured thereto adapted to depress said pin and actuate said arm, springs adapted to lift said foot upon release of said pin and withdraw said arm, posts supporting said plate, and cams disposed beneath said posts adapted to raise the same.

50 ROBERT D. GILLETTE.
